UNITED STATES PATENT OFFICE.

CYRUS MASON MOODY, OF GREENFIELD, MASSACHUSETTS.

SCHOOL AND BUSINESS TABLET.

SPECIFICATION forming part of Letters Patent No. 334,537, dated January 19, 1886.

Application filed July 30, 1884. Serial No. 139,221. (No model.)

To all whom it may concern:

Be it known that I, CYRUS MASON MOODY, a citizen of the United States, residing at Greenfield, in the county of Franklin and 5 Commonwealth of Massachusetts, have invented a new and useful Improvement in School and Business Tablets, of which the following is a true and full specification.

My invention relates to that class of tablets 10 or other means for hasty or offhand writing where generally the tablet or paper is held in the hand, or perhaps laid on a table, or, for business purposes, may be hung up.

In many branches of business it will be 15 found very convenient for taking orders and keeping memoranda, so that they can be easily preserved and referred to as desired.

My invention consists of a school or business tablet provided with two longitudinal sides 20 with grooves and two transverse partitions, forming an intermediate apartment, and a recess on either side of the same, in which are placed rollers for taking up and letting off paper, and a sliding bottom to work in grooves 25 aforesaid, all of which will be fully set forth hereinafter.

In the accompanying drawings, which illustrate my invention and form part of this specification, Figure 1 is a perspective view; 30 Fig. 2, a longitudinal section, and Fig. 3 a transverse section.

A A are the two sides of the tablet, wide enough to be the sides of the drawer E, and receiving at each of their ends the journals of 35 the rollers B B. Over the lower one is wound a slip of paper, F, about the width of the tablet, (which should be of any convenient width,) and the paper may be of any desired length, dependent on its thickness, controlled only by 40 the size of the roll. The paper passes upon the face of the tablet over the roller B at the upper end, where it is wound up. On the

under side of the tablet is made a small drawer, E, the sides of which are the sides of the tablet, each slotted so as to receive a sliding lid. 45 This drawer is intended to hold pencils, pens, crayons, rubber erasers, or any other article which is needed by pupils at school, or tickets, memoranda, and other things convenient for business use, for which purpose a wire 50 staple or other contrivance may be used to hang it up.

The operation of the tablet is easily understood. The paper, lightly stuck to the lower roller, is wound upon it to its fullest capacity. 55

The loose end is brought over the face of the tablet and stuck upon the upper roller, the ends of the board forming the tablet, which are slightly rounded, to allow the paper to pass smoothly over without creasing, which, 60 as fast as it is used, is wound up on the upper roller. In one end of each roller is secured a projecting knob or plug, C, so shaped as to be easily grasped by the thumb and finger, enabling one to turn the rollers easily to loosen or 65 wind up the paper. In the opposite end of each roller is a screw or plug, D, inserted, by which the roller may be held securely as wanted. A looped wire staple is convenient. If it works loose in the wood, it is easily re- 7c placed by a larger size at a trifling expense.

I claim—

In a school or business tablet, the box composed of two longitudinal sides provided with grooves, two partitions meeting said sides at 75 right angles, to form, with the top, an apartment, E, and two open recesses at the ends, in combination with rollers B B and a sliding bottom, all arranged substantially as and for the purpose set forth.

CYRUS MASON MOODY.
